DUMP POCKET FOR SCOWS

Application filed November 30, 1931. Serial No. 578,048.

This invention relates to dump pockets for scows, and more particularly to self closing doors for such pockets.

In the present practice, it is common to form dump scows with one or more large pockets or chambers for receiving the material to be dumped. The discharge of such material is controlled by a pair of doors, forming a bottom for the pocket, when closed, and adapted, when tripped, to swing downwardly to a vertical position. Since the material is often dumped in quite shallow water, it has been the practice to mount such doors at a sufficient elevation in the pocket to avoid their appreciable projection, when open, below the scow bottom. This has reduced the useful capacity of the pockets and has further entailed a free admission of water to the portions of the pockets below the closed doors, whereby the water resistance opposing travel has been largely increased, as compared to a vessel having a fully closed bottom.

Also, in prior practice, automatic provisions for closing the dump pocket doors have been lacking, and it has consequently been necessary either to provide expensive power-operated winches for that purpose or hand-operated mechanism requiring much time and arduous labor for its manipulation.

It has further been required in operating dump pocket doors, as heretofore constructed, to place men upon the scow to effect lowering and raising of the doors, whereby the lives of such men have been endangered in rough weather.

An object of the present invention is to so form and mount the door of a scow dump pocket as to avoid curtailment of the load capacity of said pocket, and so as to establish said door, in its closed position, substantially flush with the scow bottom.

Another object is to form the door of a scow dump pocket with an air chamber and to utilize resulting buoyancy of the door to effect its automatic closing immediately upon emptying of the pocket, thus eliminating the door-closing mechanism now commonly provided, and saving the time and

power required to operate such mechanism.

A further object is to provide a latch means automatically effective upon closing of a dump pocket door to hold such door in closed position. 55

A still further object is to adapt such latch mechanism to be readily tripped from the towing tug, eliminating the time, effort, and danger involved in sending a man or men on board the scow preliminary to dumping. 60

A still further object is to adapt the doors controlling several pockets of a dump scow to be tripped in common, and preferably in succession, from the towing tug. 65

It is also an object of the invention to employ buoyancy of a dump pocket door both to actuate the door to closed position and to cushion the impact of the door on its seat. 70

These and various other objects the invention attains by the construction hereinafter described, and illustrated in the accompanying drawings, wherein:

Fig. 1 is a view in longitudinal, side elevation of a dump scow equipped with doors and control mechanism in accordance with 75 the present invention, one of said doors being shown in dumping position and the other closed.

Fig. 2 is a top plan view of one of said pockets and its door. 80

Fig. 3 is a longitudinal sectional elevation of said pocket, taken upon the line 3-3 of Fig. 2.

Fig. 4 is a transverse sectional elevation taken upon the line 4-4 of Fig. 3. 85

In these views, the reference characters 1 and 2 designate the deck and bottom of a dump scow formed of any suitable material, and preferably of sheet metal. For receiving material to be dumped, said scow is 90 formed with one or more open-topped pockets 3, each formed by bulkheads 4 (preferably of sheet metal) rigidly extending between the bottom and deck of the scow and projecting preferably some distance above 95 the deck, so as to form a combing.

The bottom of each pocket 3 is formed by a door 5 comprising upper and lower walls spaced to form an air chamber 6, preferably coextensive in area with the door. Said door 100

in its closed position is adapted to fit snugly into the lower end of the pocket, with its under face substantially flush with the scow bottom.

5 To the under face of each door 5 is secured a suitable number of hinge members 7, mounting the door upon a shaft 8, located preferably some distance aft of the forward edge of the door. Thus, as illustrated, said shaft is positioned approximately one-third the door length from the front edge of the door. The shaft 8 has its extremities mounted in a pair of hinge members 9 secured to the scow bottom, one at each side of the pocket.

To strongly reinforce the described door and also largely protect the bulkheads 4 from material in the pocket, a pair of vertical plates 10 are upwardly extended from the lateral margins of the door, and are rigidly connected by a plate 11 secured to and rising from the forward edge of the door. Said plates extend in height approximately to the top of the pocket, when the door is closed. 25 The rear edges 12 of the plates 10 transcribe arcs substantially centered in the pivotal axis of the door, so that the plates may clear the rear bulkhead 4, as the door is swung. The door member is preferably further reinforced by a metal top plate 13, parallel to the members 5, extending rearwardly from the upper edge of the plate 11 and rigidly connecting the forward portions of the plates 10.

30 35 The rear bulkhead 4 of each pocket preferably carries within the pocket a heavy timber 14 to form a seat for the closed door and receive the impact of its closing travel.

To hold the described door normally closed, there is mounted upon the inner faces of the side plates 10 adjacent to their arcuate rear edges a pair of coaxial, peripherally grooved rollers 15, for engagement by a pair of latch bolts 16. These are preferably 40 mounted in substantially radial relation to said arcuate edges, and are slidable in suitable bearings 17 carried by the side bulkheads of each pocket. The bolts 16 project freely through the rear bulkhead and are rigidly connected above the deck 1 by a cross bar 18 which compels their travel in unison.

45 50 For retracting the described latch bolts, the mid portion of each cross bar 18 carries a socket member 19 into which extends the short lower arm of a bell crank lever 20. The latter is pivoted as indicated at 21, in close proximity to said socket members, and further comprises an upwardly extending arm of a length affording powerful leverage.

55 60 65 For actuating the levers 20 to trip the doors of the several pockets, a trip cable 22 is engaged with the upper extremity of the rearmost of said levers, and is connected through a short extension cable 23 with each of the remaining levers 20. Each extension

23 is normally sufficiently slack that it will not actuate the engaged lever until the main cable 22 has been released from such lever or levers 20 as are rearward of that engaged by said extension. Attachment of the cable 22 and its extension 23 to the levers 20 is established preferably through loops 23a slipped over the upper ends of said levers, the arrangement being such that upon actuation of any lever 20 to its forwardly inclined latch-tripping position the resulting lever incline permits release of the trip line or its extension from such lever by a continued pull on the line. Thus, it is seen that the cable 22 with its extension (or extensions) provides a means for tripping the several levers 20 in a succession, which progresses from stern to bow of the scow.

This arrangement also makes possible attachment of the trip line to the several levers 20 subsequent to loading of the scow and prior to towing of same to the dumping point. Since the loading location of the scow is generally well sheltered, it follows that attachment of the tripping lines to the levers entails no serious danger, even in rough weather. This is not the case if men were required to board the scow at the point of dumping, as in prior practice. It will, of course, be understood that the tripping line is extended to the towing tug and is operable therefrom.

65 70 75 Following a retraction of the bolts 16, the latter will ordinarily be returned by gravity to their latching positions upon discontinuance of the tripping effort. It is preferred, however, to associate with each cross bar 18 a coiled spring 24 effective to positively project the latch bolts connected by such bar.

80 85 90 Opening travel of the pocket doors is suitably limited, as for example by mounting a pair of stop blocks 25 upon the ends of the top plate 13 for engagement with the bearings 17. An approximate 45-degree inclination of the described doors in their limiting open positions is amply sufficient to effect discharge of the load.

95 100 105 The door 5 is suitably interiorly reinforced as by a series of spaced I-beams 26 extending longitudinally thereof within the air chamber 6.

110 115 120 The floor-forming surface of the door 5 and the interior face of the plate 11 are preferably covered by a lining 27 of wood to take such abrasion as is incidental to loading and discharging of material, said lining being conveniently renewable.

125 130 135 An important feature of the described invention is the self-closing operation of the described doors. Thus, immediately upon emptying of any pocket, buoyancy secured by provision of the air chamber 6 serves to promptly effect an automatic closing of the door of such pocket. It is to be noted that the buoyant force exerted by the portion of

the chamber 6 located forwardly of the pivotal axis predeterminedly opposes closing travel, thus cushioning the seating impact of the door and reducing the violence of its opening travel.

It is in many instances desirable to operate dump scows during freezing weather. Heretofore operation during such weather has proven very troublesome owing to the 10 hopper contents forming a single frozen mass and consequently refusing to discharge upon opening of the doors.

The present invention provides for elimination of such trouble by adapting the chamber 6 to be filled, during loading of the scow with live steam. Thus sufficient heat is communicated to the material before towing to the dumping point to avoid freezing of the material during such towing.

20 Preferably steam delivery and discharge pipes 28 and 29 extend upward from the chamber 6 adjacent to the plate 11, and each preferably also adjacent to one of the plates 10. The delivery pipe projects sufficiently 25 above the plate 13 to permit attachment of a steam-supplying hose or pipe (not shown) thereto, while the pipe 29 need merely open to the atmosphere through said plate. Preferably the discharge pipe has a capacity considerably less than that of the delivery pipe 30 so as to build up a slight pressure of steam in the chamber 6.

As compared to the practice now common of employing a pair of dump pocket doors 35 pivoted to swing on axes at each side of the pocket, parallel to the direction of travel of the scow, numerous features of superiority are present in the described construction. As has been pointed out, the latter offers a much 40 lesser resistance to travel of the scow than present constructions. It is further to be noted that the described type of door permits unloading of the scow in much shallower water than has heretofore been permissible. Thus, the scow bottom may, if desired, 45 be grounded when the doors are tripped. The weight of the doors and their load is then largely transferred to the ground surface underlying the scow, thus very materially lightening the latter and permitting it to correspondingly rise. This so increases the 50 degree of opening of the doors that, even though their discharge inclination be slight, the pockets may be readily emptied by advancing the scow.

While it is apparent that the illustrated embodiment of my invention is well calculated to adequately fulfill the objects and advantages primarily stated, it is to be understood that the invention is susceptible to variation, modification and change within the 60 spirit and scope of the subjoined claims.

What I claim is:

1. In a scow having a dump pocket, a door 65 pivoted adjacent to the bottom of said pocket

upon an axis transverse to the direction of normal travel of said scow, said door having plates rising from its lateral edges and a plate rising from one of its transverse edges and rigidly connecting the first mentioned plates. 70

2. In a scow having a plurality of dump pockets, doors controlling the discharge from said pockets, latch mechanisms holding said doors normally closed, and means to successively trip said latch mechanisms operative 75 from a point remote from said mechanisms.

3. In a scow having a dump pocket, a door normally forming a bottom for said pocket and pivotally downwardly actuatable to an open position, and means within said pocket 80 limiting opening travel of said door.

4. In a scow having a dump pocket, a door controlling the discharge from said pocket, formed with a steam chamber for heating the pocket contents, and means for delivering 85 steam to and discharging it from said chamber.

5. In a scow having a dump pocket, a door controlling the discharge from said pocket, formed with an air chamber imparting to 90 said door a buoyancy adequate to effect its automatic closing, and means for delivering steam to and from said chamber for heating the contents of the pocket in freezing weather. 95

6. In a scow having a dump pocket, a door controlling said pocket, pivoted adjacent to the lower end of said pocket, and having its pivotal axis transverse to the scow, said door being formed with an air pocket having a 100 major portion extended aft and a minor portion extended forward of its pivotal axis, whereby said door is rendered buoyantly self-closing and is buoyantly cushioned in its closing travel. 105

In testimony whereof I sign this specification.

WILLET A. SESSION.
